UNITED STATES PATENT OFFICE

105,278

DESIGN FOR A REFRIGERATED SHOWCASE

Joseph Stuart Hill, Hillwood Lakes, N. J., assignor to C. V. Hill & Company, Incorporated, Trenton, N. J., a corporation of New Jersey

Application September 3, 1936, Serial No. 64,706

Term of patent 7 years

To whom it may concern:

Be it known that I, Joseph Stuart Hill, a citizen of the United States, residing at Hillwood Lakes, in the county of Mercer, State of New Jersey, have invented a new, original, and ornamental Design for a Refrigerated Showcase, of which the following is a specification, reference being had to the accompanying drawing, forming part thereof.

Fig. 1 is a front perspective view of a refrigerated showcase showing my design;

Fig. 2 is a top plan view thereof; and

Fig. 3 is a rear perspective view thereof.

I claim:

The ornamental design for a refrigerated showcase as shown.

JOSEPH STUART HILL.
